BRUSH HOLDER CONSTRUCTION FOR DYNAMO ELECTRIC MACHINES

Theodor Gutherlet, Giessen, Germany, assignor to Schunk & Ebe G.m.b.H., Giessen, Germany, a corporation of Germany

Filed May 31, 1960, Ser. No. 33,057
9 Claims. (Cl. 310—246)

This invention relates to a brush construction for dynamo electric machines and is particularly concerned with an existing class of brush holders that can be improved by eliminating the usual shunt connections that are ordinarily employed and by providing a structure that commutes directly with the brush, all without change in the basic design of the brush holder, it being a general object of this invention to avoid the deficiencies attendant to the use of shunt connections on brushes and that often become loosened and ineffective.

Reference is made to applicant's copending application Serial No. 849,790 filed October 30, 1959, now Patent No. 3,049,037, entitled Brush Holders for Electrical Machinery.

The railroads, for instance, extensively use a brush holder of the general type under consideration and wherein there is a thrust lever that transmits force through an arcuate path to the brush, the difference between that arcuate path and the rectilinear path of the brush in the holder being compensated for by displacement of a thrust member on the top plane of the brush. In twin brushes, as herein disclosed, the thrust member rests in a recess in the top of the brush in order that the thrust may be applied to both parts of said brush. The difference then between the arcuate path of said thrust member and the rectilinear path followed by the brush is usually compensated for by resiliently mounting a thrust finger in a thrust lever.

It is common practice in brush holders of this type to employ shunts, or "pig-tails," from the brush per se to a terminal on the brush holder, and although this procedure and arrangement of parts has been used for many years there has always been the danger of these shunts coming loose. As a result, the ordinary brush holders of this type are often damaged by arcing at improper points, resulting in untimely shut-down and repairs of the equipment involved.

Improvements are obtained by the present invention by use of a contact that engages and biases the brush and which is connected to the brush holder by a shunt cable. The biasing mechanism, which is similar in some respects to the mechanism disclosed in my above mentioned copending application Serial No. 849,790, is characterized by pivoted and articulated parts and it is imperative that electrical current does not pass through the pivoted connections that are provided. Therefore, the provision of the shunt cable becomes necessary together with insulation of said mechanism from the contact that engages the brush. As a result, the usual shunt that is necessary on ordinary brushes is eliminated and the brushes become simple blocks of carbon, or the like, and they can be more readily removed and replaced with considerably less effort, time and expense.

It is an object of this invention to obviate the above mentioned disadvantages by incorporating the shunt connection in the brush holder construction and eliminating it from the brush, thereby providing a very reliable structure and greatly simplifying the brush construction. With the relationship of parts and elements as herein disclosed brushes can be removed and/or replaced with facility and expediency all to the end that the invention is extremely useful and practical.

Another object of this invention is to provide a brush

2

holder for dynamo electric machinery and wherein there is little or no danger of malfunction of the parts involved, and especially no danger of the shunting of the brushes to become disconnected. With the structure herein disclosed the brushes are contacted mechanically and the shunt that I provide protects the mechanism involved and so that there is no danger of arcing at improper points.

It is still another object of this invention to provide a brush contact and biasing mechanism that can be used or employed in connection with existing brush holder designs, all without change in said existing brush holders.

Further, it is an object of this invention to provide a very simple and inexpensive brush controlling mechanism and wherein the parts involved are easy to make and reliable in their operation to bias the brush, to make electrical contact therewith, and to damp undesirable vibrations that may otherwise occur.

The various objects and features of this invention will be fully understood from the following detailed description of the preferred form and application thereof throughout which description reference is made to the accompanying drawings, in which:

FIG. 1 is a side elevation of the brush holder of the present invention, showing it related to the periphery of a commutator and with portion broken away to show in section.

FIG. 2 is a plan view taken as indicated by line 2—2 on FIG. 1 and illustrates the normal width of the device and the length of the brush engaged thereby.

FIG. 3 is a sectional view of a portion of structure of the present invention and taken as indicated by line 3—3 on FIG. 1.

The brush construction of the present invention is adapted for use, generally, in dynamoelectric machines, such as, for example, electric motors and/or generators, and in any like situation where commutation of electrical current is required. That is, the brush construction is adapted to be used in connection with commutators and sliprings to apply pressure to a brush along its longitudinal axis and to conduct electrical current to and/or from the commutator and slip-rings. As shown in the drawings, the invention involves, generally, a brush holder 1 that slidably carries a brush 2, to guide it into engagement with a commutator 10, a thrust lever 4, a thrust finger 5 with a thrust member 6 engageable with the brush 2, a vibration damping means 9 supporting the thrust member 6 on the thrust lever 4, a link 8 pivoted relative to the holder 1 and pivotally carrying the thrust lever 4, bias means 3 to urge the thrust lever and member into pressured engagement with the brush 2, and a shunt cable 11 extending between the thrust finger 5 and the brush holder 1.

The brush holder 1 is a frame-like part adapted to guide and direct the brush 2 into engagement with the periphery of the commutator 10 and is of the usual construction and mounted on insulators at 15. The periphery of the commutator 10 is arcuate with the holder guiding the brush 2 so that it projects radially of the commutator, the holder 1 and brush 2 being of substantial length in order to allow for long wear of said brush.

In accordance with the invention, one side of the holder is open or slotted at 20 in order to permit depressing of the brush 2 by the thrust finger 5 and there is a lug 21 that is positioned laterally of the slotted side of the holder, at the top side thereof and substantially spaced from the brush 2, to cooperatively carry and relate the link 8 and thrust lever 4.

The brush 2, as shown throughout the drawings, is a twin brush of carbon, or the like, in that it involves a pair of like brush sections 22 and 23. The drawings indicate the separate independent sections 22 and 23, as they are guided by the holder 1 and accessible through the slotted

opening at 20. In accordance with the invention, the sections 22 and 23 are arranged face to face in lateral engagement and there is a notch 22' and 23' at the upper end of each section, respectively, said notches being arcuate and cooperatively forming a semi-circular seat or recess 7. Thus, the recess 7 is at the upper end of the brush 2 and adapted to receive the thrust member 6.

The link 8 is pivotally carried by the holder 1, being pivotally connected to the lug 21 by a pin 25 to project upwardly and substantially parallel with the brush 2. The pivotal axis of the link 8 is removed laterally from the portion of the holder that carries the brush and is disposed parallel with the commutator axis and parallel with the adjacent side of the brush 2. In practice, the axis of the pin 25 is at or near a plane substantially coincident with and tangent to the periphery of the commutator.

The thrust lever 4 is pivotally carried by the link 8 being pivotally connected to the upper and outer swinging end portion of the link 8 by a pin 26 to project and swing toward the brush 2. The pivotal supporting axis of the lever 4 is parallel with the above described pivotal axis of the link 8.

The thrust finger 5 is a continuation of and extends inwardly from the outer swinging end portion of the thrust lever 4 and is resiliently coupled thereto by the vibration damping means 9. As shown, the lever 4 and thrust finger 5 are coupled by an insulating structure that comprises a head 27 that carries the damping means 9 which comprises a body of rubber, or the like, that is resilient and electrically isolates and yieldingly mounts the finger 5 on the outer end portion of the lever 4. More particularly, the thrust finger 5 comprises a substantially flexible part that projects from the damping means 9 and carries the thrust member 6 to engage the top end of the brush 2. In accordance with the invention, the thrust member 6 is carried at the terminal end of the finger 5 and is a cylindrically-shaped part with its lower periphery suitably coated or plated with conductive material and engaged in and seated in the recess 7, the member 6 and recess 7 being formed on a common axis parallel with the axes of the above mentioned pins 25 and 26.

The head 27 is an inverted U-shaped part made of metal having, primarily, a transverse plate portion and in the preferred form it is a part separate from the lever 4 and has spaced depending side cheeks for connection with the lever 4. Further, in the preferred form of the invention, the lever 4 involves spaced parallel elements in which case each of said latter elements is engaged with and connected to a cheek of the head 27. In the drawings I have shown the lever elements joined to the cheeks of the head by means of spaced pins 28 engaged therethrough, said cheeks being spaced by sleeves 29 surrounding the pins. In the case illustrated the pins 28 are rivets that draw the parts into tight engagement, with the head 27 rigid with lever 4. The body of rubber, or the like, that forms the damping means 9 surrounds the plane portion of the head 27 and the thrust finger 5 has a portion thereof wrapped around the said rubber, or vibration damping body thereof, and clamped as clearly illustrated by the forwardmost rivet fastener, as shown.

The bias means 3 is preferably a spring bias means and involves a spring 30 that is tensioned and engaged with the outer end of the thrust lever 4 in the form illustrated, the spring 30 is a clock-type spring carried on a selectively rotatable bolt 32 securing the spring 30 to the holder 1 and the spring 30 has a free and active end that engages one of the pins 28 that couples the lever 4 to the head 27. In practice, the pins 28 are positioned just below the plate portion of the head 27.

In accordance with the invention, I provide the shunt cable 11 that extends between the thrust finger 5 and brush holder 1. The cable 11 is flexible in order to provide freedom of movement in the parts thus far described and the cable 11 serves to transmit current from the

5 holder 1, respectively.

The parts and elements, as above described, are related to each other and operate as follows: The twin brush 2 guided in the brush holder 1 is pressed against the commutator 10 by the tension spring 30 acting by way of the lever 4, thrust finger 5 and thrust member 6 which engages in the recess 7 in the brush top. The difference between the arcuate path described by the thrust member 6 and the rectilinear path described by the brush 2 is compensated for between various positions by the link 8 disposed between the lever 4 and the holder 1.

From the foregoing it will be apparent that the thrust lever is biased by a spring pressure that is translated into thrust extending longitudinally of the brush. The usual difficulty of shunted brushes is overcome in the holder according to the invention by the provision of the shunt cable 11 which directly connects the brush to the holder through the cooperative relationship of the thrust member 6 that commutes with the brush 2 at the recess 7. This cooperative relationship is furthered by the provision of conductive plating on the surface of the said thrust member 6 and which is particularly adapted to conduct current to or from the twin brush 2. It will be apparent that any electrical load is therefore carried through the thrust member 6, thrust finger 5 and cable 11, and under no circumstances is there any danger of conduction through the mechanical parts involved in the biasing mechanism, mainly the pin connections 25 and 26. Further, it will be apparent that the damping means 9 electrically isolates the thrust finger 5 from the thrust lever 4, both electrically and mechanically. That is the thrust finger 5 and thrust lever 4 are separated so that current does not flow therebetween and so that mechanical vibrations are not carried from one part to the other.

Having described only the typical preferred form and application of my invention, I do not wish to be limited or restricted to the specific details herein set forth, but wish to reserve to myself any variations or modifications that may appear to those skilled in the art and fall within the scope of the following claims.

45 Having described my invention, I claim:

1. A brush construction to urge a brush into engagement with a commutator and the like, and including, a holder to shiftably carry and to guide the brush, a link pivoted on the holder laterally of the brush, a thrust lever pivotally carried on the link and supporting an insulated thrust member mechanically and electrically contacting the brush, bias means acting on the thrust lever and said member to move the brush as it wears, and the brush current being conducted by an electrical shunt extending from the thrust member.

50 2. A brush construction to urge a brush into engagement with a commutator and the like, and including, a holder to shiftably carry and to guide the brush, a link pivoted on the holder laterally of the brush, a thrust lever pivotally carried on the link and supporting an insulated thrust member mechanically and electrically contacting the brush, bias means acting on the thrust lever and said member to move the brush as it wears, and the brush current being conducted by an electrical shunt extending between the thrust member and the holder.

65 3. A brush construction to urge a brush into engagement with a commutator and the like, and including, a holder to shiftably carry and to guide the brush, a link pivoted on the holder laterally of the brush, a thrust lever pivotally carried on the link and supporting an insulated thrust member mechanically and electrically contacting the brush, bias means acting on the thrust lever and said member to move the brush as it wears, and the brush current being conducted by a flexible electrical shunt extending between the thrust member and the holder.

4. A brush construction to urge a brush into engagement with a commutator and the like, and including, a holder to shiftably carry and to guide the brush, a link pivoted on the holder laterally of the brush, a thrust lever pivotally carried on the link and extending toward the brush, a thrust member supported by the thrust lever and mechanically and electrically contacting the brush as it wears, there being electrical insulation between the thrust lever and thrust member, bias means acting on the thrust lever to urge said thrust member into contacting engagement with the brush, and the brush current being conducted by an electrical shunt extending from the thrust member.

5. A brush construction to urge a brush into engagement with a commutator and the like, and including, a holder to shiftably carry and to guide the brush, a link pivoted on the holder laterally of the brush, a thrust lever pivotally carried on the link and extending toward the brush, a thrust member supported by the thrust lever and mechanically and electrically contacting the brush as it wears, there being electrical insulation between the thrust lever and thrust member, bias means acting on the thrust lever to urge said thrust member into said mechanical and electrical contacting engagement with the brush, and the brush current being conducted by an electrical shunt extending between the thrust member and the holder.

6. A brush construction to urge a brush into engagement with a commutator and the like, and including, a holder to shiftably carry and to guide the brush, a link pivoted on the holder laterally of the brush, a thrust lever pivotally carried on the link and extending toward the brush, a thrust member supported by the thrust lever and mechanically and electrically contacting the brush as it wears, there being a body of resilient insulating material between the thrust lever and thrust member, bias means acting on the thrust lever to urge said thrust member into said mechanical and electrical contacting engagement with the brush, and the brush current being conducted by an electrical shunt extending from the thrust member.

7. A brush construction to urge a brush into engagement with a commutator and the like, and including, a holder to shiftably carry and guide the brush, a link pivoted on the holder laterally of the brush, a thrust lever pivotally carried on the link and extending toward the

40

45

brush, a thrust member supported by the thrust lever and mechanically and electrically contacting the brush as it wears, there being a body of resilient insulating material between the thrust lever and thrust member, bias means acting on the thrust lever to urge said thrust member into said mechanical and electrical contacting engagement with the brush, and the brush current being conducted by an electrical shunt extending between the thrust member and the holder.

10 8. A brush construction to urge a brush into engagement with a commutator and the like, and including, a holder to shiftably carry and to guide the brush, a link pivoted on the holder laterally of the brush, a pair of thrust levers pivotally carried on the link and extending 15 toward the brush, a thrust member supported between the thrust levers and mechanically and electrically contacting the brush as it wears, there being electrical insulation between the thrust levers and thrust member, bias means acting on the thrust levers to urge said thrust member into said mechanical and electrical contacting engagement with the brush, and the brush current being conducted by an electrical shunt extending from the thrust member.

15 9. A brush construction to urge a brush into engagement with a commutator and the like, and including, a holder to shiftably carry and to guide the brush, a link pivoted on the holder laterally of the brush, a pair of thrust levers pivotally carried on the link and extending 20 toward the brush, a thrust member supported between the thrust levers and mechanically and electrically contacting the brush as it wears, there being electrical insulation between the thrust levers and thrust member, bias means acting on the thrust levers to urge said thrust member into said mechanical and electrical contacting engagement with the brush, and the brush current being conducted by an electrical shunt extending between the thrust member and the holder.
